RINSAI MAEDA, OF SEATTLE, WASHINGTON

TOOL FOR TIGHTENING WIRE FASTENERS OVER CONTAINER COVERS

Application filed March 18, 1932. Serial No. 599,646.

This invention relates to tools for tightening wires and particularly wires for holding covers on containers.

In the use of various forms of containers and especially hampers it has been found advisable to utilize wire loops adapted to be tightened over the covers of such containers. Such wires cannot be satisfactorily tightened manually as they tend to cut into the hands of the operator when sufficient force is applied, and it is also difficult to supply sufficient force by the hands alone. It is also impractical to move such containers to a machine for such tightening and is important therefore that a simple portable tool be supplied for that purpose.

It is therefore one of the objects of this invention to provide a light portable tool of simple construction which may be easily made and carried about for use and applied for tightening the wires on such hampers etc., wherever they may be.

A further object is to provide such tool as a mandrel or rod for tightening such wires. Such rod made with a slot in one end for securely holding a portion of such wire; and a shank for twisting additional portions of the wire around the same, till the cover is securely bound upon its seat by the wires, and which tool may be then easily detached from the wire.

With these and other objects I have illustrated my invention by the accompanying drawing, of which:

Figure 1 represents a top plan of my assembled tool,

Figure 2 represents an edge view thereof with parts removed,

Figure 3 represents an end view, taken from the right hand side of Figure 1,

Figure 4 shows a perspective view of the assembled tool, applied against a side of a hamper, with a cover wire attached,

Figure 5 shows a perspective view of the assembled tool, positioned on the top of the hamper for drawing two cover bails toward each other with a tie wire attached to the tool,

Figure 6 shows a detail view of the winding mandrel or rod which may be utilized for

tightening the wires in some cases without the other parts of the assembled tool,

Figure 7 represents a fragment of a hamper, with one of the cover bail wires threaded through a fulcrum eye on the side of the hamper, and the end of such wire held in the slot, for twisting the wire around the mandrel to tighten the bails.

Like numerals on the different figures represent like parts.

Numeral 8 represents the upper part of any hamper or container on which a cover 9 is to be held in place by a plurality of wire loops or bails as 10 and 11. The ends of such bails are either all attached to the top of the container, as shown in Figure 5, or designed to be attached thereto, when tightened as indicated in Figure 4.

The assembled tool comprises a yoke frame 12, with a triangular abutment plate 13 attached to the lower end thereof, adapted to fit into the angle formed by the bail 10, when positioned on top of the cover, as shown in Figure 5, or to serve as a footing when positioned against the rim of the container as shown in Figure 4. Holding lugs 14 are adjustably attached to the lower end of the plate 13, to retain the tool in suitable position when used as shown in Figure 4. A notch 15 is cut across the apex of the plate near the lower end thereof, to retain the bail 10 in suitable position over the plate when it is used as indicated in Figure 5 for tightening the bails.

The most important part of the assembled tool is a tapered ended winding mandrel or rod 16. This may be rotatably mounted through the frame, to be turned by any means, as a crank 17 or by a lever 18 slidably positioned through holes in one end of the rod, or by a socket wrench applied to the squared end 19 thereof.

The opposite end of the rod is constructed with a slot therein, which provides oppositely positioned jaws 20-20. Between these jaws the end or portion of a wire 11' to be tightened is positioned and held. As the rod is then rotated, the body of the wire is twisted around the rod till the wire or wire

bails are sufficiently tightened, as indicated in Figures 4, 5 and 7.

When the rod is used in the assembled tool, the operator after such tightening tilts the 5 tool in the direction indicated by the arrows, and the body or bend of the wire will be held from slipping back by its sharp bend over the fulcrums, as the fixed eyelet 21 in Figure 4, or over the bail wire 10 in Figure 10 5. The rod is then slipped from wire coils and the coils cut away and the free end of the tightened wire then manually twisted beneath its body as indicated by dotted lines 22 in Figure 4, and so locked.

15 The most important features of the winding rod are the holding jaws and a tapered slope of the part of the rod whereon the wire is wound. The slope permits the rod to be easily withdrawn from the coils when the 20 wire has been tightened. This tapered form is best shown in Figure 6, whereon the rod is seen to decrease in diameter from the point indicated at 23, gradually down to the ends of the jaws 20. Without this slope the coils 25 when wound around the rod, would bind, and prevent the quick or easy separation thereof.

When used in the assembled form the rod 30 may be provided with a ratchet wheel 24, and pawl 25, to prevent the rod turning backward. This assembled construction is particularly important when required for heavy 35 duty.

For light work the rod may be generally 35 used for tightening without the frame. As shown in Figure 7. There the rod is positioned adjoining the fulcrum eye 21, and the wire end 11' inserted between the jaws, and 40 then as the rod is turned the body of the wire when so drawn through the eye is maintained on an open curve by the rod, and so

slides through the eye more freely than it would if guided directly back over the top of said eye. When sufficiently tightened this wire may be bent abruptly back over the eye, and the rod withdrawn, and the free end of 70 the wire locked as described.

Having described my invention I claim as new for Letters Patent:

1. A tool for tightening wire fasteners over container covers, comprising a holding 75 frame, an angular abutment plate on the lower end of the frame for holding the tool in suitable position against the top and side of the container, a winding rod rotatably mounted through the frame with means for turning the rod at one end thereof, and the other end provided with oppositely positioned jaws adapted for holding a wire to be twisted upon the rod, the jaw end of the 80 rod tapered and increasing in diameter from the end of the jaws for a distance over which the wire may be wound, said taper to facilitate the separation of the rod from the wire coils when the wire has been tightened.

2. A tool for tightening wire fasteners over container covers, comprising a holding frame, an abutment block on one end of the frame, provided with a notch for holding a wire while being tightened, adjustable lugs 85 extending from the block to hold the same in position when a wire is tightened, a mandrel provided with a slot in one end for holding a portion of the wire, to be twisted around the mandrel, the outside of the mandrel tapered back from the jaw end to facilitate separation thereof from the wire, the mandrel rotatably mounted in the frame with means for turning the same.

In testimony whereof I affix my signature.

RINSAI MAEDA.
